UNITED STATES PATENT OFFICE.

CLAIR L. FARRAND, OF FOREST HILLS, NEW YORK, AND ERNEST ROSS, OF EAST ORANGE, NEW JERSEY; SAID ROSS ASSIGNOR TO FARRAND MFG. CO. INC., OF LONG ISLAND CITY, NEW YORK, A CORPORATION OF NEW JERSEY.

LOUD SPEAKER.

Application filed November 5, 1926. Serial No. 146,352.

This invention relates to loud speakers and more particularly to a clamping ring structure which supports the diaphragm.

The clamping ring structure forming the subject matter of this application was designed especially for use in a loud speaker having a large cone shaped diaphragm, but it may be used with diaphragms of other types. Heretofore in loud speakers of the cone type employing metallic clamping rings for the diaphragm it has been necessary to cast the rings or make them by some such expensive method and it has been necessary to clamp the rings to the edge of the diaphragm by individual fastening devices such as bolts, screws or the like. The main object of this invention is to provide a ring structure so designed that all of its parts may be stamped from sheet metal. A further object of the invention is to provide a ring structure, the rings of which may be interlocked and clamped together by integral portions associated with the ring structure thus eliminating the necessity of employing additional fastening devices.

The accompanying drawings illustrate a loud speaker of the cone type having a ring structure for the diaphragm constructed in accordance with the invention.

In the drawings—

Fig. 1 is an elevation of the loud speaker; Fig. 2 is a side elevation, partly in section on the line 2—2 of Fig. 1;

Fig. 3 is a partial transverse section through the ring structure taken on the line 3—3 of Fig. 1; and

Figs. 4 and 5 are detail views showing the rings by themselves.

The particular type of loud speaker shown in the drawings comprises a diaphragm structure which includes a cone 1 and a frustum of a cone 2. The cone and cone frustum are united at their edges and an ornamental cord 3 encircles the diaphragm structure so formed to conceal the joint between the cone and the cone frustum. The other edge of the cone frustum 2 is clamped in the ring structure which forms the subject matter of this invention. The ring structure comprises an inner ring 4 stamped from sheet metal. It is stamped in such a way as to form along

its inner edge a series of integral tongues 6 (Fig. 5). The ring structure also comprises an outer ring 7 which is also stamped from sheet metal and so formed as to provide a series of openings 8 located so that their spacing corresponds with the spacing of the tongues 6 on the ring 4 and so that each opening 8 is adapted to receive one of the tongues 6. When the rings are applied to the diaphragm in the manner hereinafter described, each of the tongues 6 is forced through a corresponding opening 8 in the outer ring 7 and is bent over and against the face of the outer ring to clamp the two rings to the edge portion of the diaphragm as clearly shown in Figs. 1, 2 and 3. The outer ring 7 is also so shaped as to provide a turned over edge portion 9 which forms an annular recess or pocket adapted to receive a ring 10 which is made expansible and contractible by dividing it as at 10' (Fig. 1). This ring may also be a metal stamping. Its purpose is to hold in place a foraminous closure for the central opening in the ring structure. This closure may comprise a ring 11, made of pasteboard or the like, which forms a support for a fabric or screen 12 which extends across the open center of the ring structure. The clamping rings are applied to the cone structure by properly positioning them with respect to the edge of the diaphragm and then by suitable mechanical means, such as an automatic machine designed for the purpose, the tongues 6 on the inner ring 4 are forced through the openings 8 and are bent over against the surface of the outer ring 7 in the manner above described. It will be understood that this operation is performed before the expansible ring 10 and the closure 11—12 are in place.

The outer ring 7 is also provided with an upper flange section 13 and a lower flange section 14. By means of these flange sections the ring structure may be attached to a pair of supporting rods 15 by screws 16 passing through openings 17 in the flange sections only one of the rods 15 shows in Fig. 2 as the other is directly behind it in this view. The rods 15 are preferably housed within the cone structure formed by the cone 1 and the cone frustum 2 and in the finished speaker

are concealed by the fabric or screen 12. The rods pass downwardly through an opening 18 (Fig. 1) in the lowermost part of the cone structure and are secured to a supporting base 19 as shown at 20. The particular manner of constructing the supporting base and of attaching the rods to the supporting base forms no part of the present invention but is more fully disclosed in certain other co-pending applications. The rods 15 also constitute a support for an electromagnetic actuating device 21 having an actuating rod 22 connected to the apex of the cone 1 to vibrate the latter in the well known manner.

15 In practice when assembling loud speakers of the type herein disclosed it has been found more convenient to apply the clamping ring structure to the cone frustum 2 before the cone frustum is united with the 20 cone 1. After the complete cone structure is formed with the clamping rings attached to it, the ring structure is secured to the rods 15 by means of the screws 16. However, the particular sequence of steps employed in assembling the speaker is immaterial to this invention. One of the last steps in assembling the speaker is the application of the closure 11-12 and of the expansible ring 10 which holds the closure in place. 30 The closure 11-12 abuts against an adjacent surface of the clamping ring 7 as shown in Fig. 3.

The particular type of speaker disclosed in the drawings includes a knob or handle 23 which constitutes convenient means of transporting the loud speaker from one place to another. It may be held in place by means of a screw 24 which is inserted through an opening 25' provided in the outer ring 7 before the clamping rings are assembled, the head of the screw being positioned between the two rings and the outer ring being provided with a depression 25 to accommodate the head of the screw as shown in Fig. 2. The ring 11 of the closure 11-12, as well as the expansible ring 10, should each be provided with an opening that slips over the projecting screw 24 when these parts are assembled. After the closure 11-12 and the expansible ring 10 are positioned in place the knob 23 is threaded on to the projecting screw 24.

As all of the parts of the ring structure are metal stampings the process of making them is greatly simplified and the cost is considerably reduced. However, the rings are so designed that in spite of their simplicity and inexpensive nature the appearance of the finished speaker is in no way detrimentally affected. By the use of suitable machinery all of the tongues on one ring may be forced through the corresponding openings in the other ring and bent over in the manner above described. This operation may be more quickly performed than

the operation of assembling rings of the cast type, for instance, where the fastening devices have to be individually applied and tightened. The ring structure herein disclosed is of particular value for use in any 70 loud speaker manufactured on a large scale as the rings may be expeditiously formed and quickly applied.

It will be understood that while the particular loud speaker shown in the drawings has a diaphragm of the double cone type, the ring structure either with or without suitable modifications may be used for supporting practically any type of diaphragm.

Certain other details of the loud speaker disclosed but not claimed herein are claimed in other copending applications. The construction of the pedestal is claimed in our application, Serial No. 146,353, filed November 5, 1926 and the edge construction of the diaphragm including the ornamental cord 3 or its equivalent is claimed in an application filed jointly by ourselves and Paul F. Godley, Serial No. 146,347. The manner of supporting the diaphragm structure on the pedestal including the rods 15 passing through the interior of the cone structure is claimed in application Serial No. 146,348 filed jointly by ourselves and Paul F. Godley, on November 5, 1926.

We claim:

1. In a loud speaker a diaphragm, and a pair of clamping rings between which the edge portion of the diaphragm is clamped, one of said rings having a series of openings and the other of the rings having a series of tongues, each of said tongues being inserted through one of said openings and bent over against the face of the other ring to clamp the two rings against the edge portion of the diaphragm. 100

2. In a loud speaker a diaphragm and a pair of clamping rings between which the edge portion of the diaphragm is clamped, one of said rings having tongues bent over portions of the other rings to clamp the two rings against the edge portion of the diaphragm. 110

3. In a loud speaker a diaphragm and a pair of sheet metal clamping rings between which the edge portion of the diaphragm is clamped, a portion of one of said rings being bent over into engagement with a portion of the other ring to clamp the two rings to the edge portion of the diaphragm. 115

4. In a loud speaker a diaphragm and a pair of sheet metal clamping rings between which the edge portion of the diaphragm is clamped, integral portions of one of said rings being bent over portions of the other ring to clamp the two rings against the edge portion of the diaphragm. 125

5. In a loud speaker, a diaphragm and a pair of sheet metal clamping rings between 130

which the edge portion of the diaphragm is clamped, one of said rings having integral portions engaging and interlocked with the other ring to clamp the two rings against the edge portion of the diaphragm.

6. In a loud speaker a diaphragm, a pair of rings between which the edge portion of the diaphragm is clamped one of said rings having an inturned edge portion to form an annular seat and an expansible ring held in said sheet.

7. In a loud speaker a diaphragm, a pair of rings between which the edge portion of the diaphragm is clamped one of said rings having an inturned edge portion to form an annular seat, a member constituting a fo-

raminous closure for the open center of the rings and an expansible ring held in said annular seat against said member.

8. In a loud speaker a diaphragm and a 20 clamping ring structure comprising a pair of sheet metal clamping rings interlocked with each other to clamp the edge portion of the diaphragm between them, and a support for the ring structure, one of said rings being provided with integral flanges adapted to be secured to said support. 25

In testimony whereof we affix our signatures.

CLAIR L. FARRAND.
ERNEST ROSS.
